SINK

George W. Hain, Birmingham, Mich., assignor to Lyon
Incorporated, Detroit, Mich., a corporation of Dela-
ware

Filed Dec. 6, 1961, Ser. No. 67,816

Term of patent 14 years

(Cl. D4—2)

FIG. 1

FIG. 2

FIG. 3

FIG. 4

FIG. 1FIG. 2FIG. 3FIGURE 1 is a perspective view of a sink showing my new design;

FIGURE 2 is a front elevational view of the sink;

FIGURE 3 is a sectional view taken substantially on the line III-III of FIGURE 1;

FIGURE 4 is a sectional view taken substantially on the line IV-IV of FIGURE 1;

FIGURE 5 is a top plan view of a modification of the sink;

FIGURE 6 is a front elevational view of the sink of FIGURE 5; and

FIGURE 7 is a sectional view taken substantially along line VII-VII of FIGURE 5.

The rear of the article not shown is substantially plain. The rear of the upstanding portion not shown is substantially like the front shown.

The dominant features of my design reside in the portions shown in full lines.

I claim:

The ornamental design for a sink, substantially as shown and described.
